UNITED STATES PATENT OFFICE.

ORÉUS L'HEUREUX, OF ST. PAUL DE CHESTER, QUEBEC, CANADA.

LEVEL.

986,924.

Specification of Letters Patent. Patented Mar. 14, 1911.

Application filed July 30, 1910. Serial No. 574,693.

To all whom it may concern:

Be it known that I, ORÉUS L'HEUREUX, millwright, of St. Paul de Chester, county of Arthabaska, Province of Quebec, Dominion of Canada, subject of the King of Great Britain, have invented certain new and useful Improvements in Levels; and I do hereby declare that the following is a full, clear, and exact description of the same.

10 The invention relates to improvements in levels, as described in the present specification and illustrated in the accompanying drawings that form part of the same.

15 The invention consists essentially in the novel construction and arrangement of parts whereby the true incline of a plurality of inclined surfaces may be determined by an attachment to a level which brings said level to a horizontal plane on one of said surfaces.

20 The objects of the invention are to facilitate the building of structures having roofs or other parts with inclined beams or surfaces, and to provide an instrument of simple, cheap and durable construction.

25 In the drawings, Figure 1 is a side elevation of the level applied to an inclined beam. Fig. 2 is an enlarged perspective view of one end of the level block partially in section. Fig. 3 is an enlarged perspective detail of the elevating plate and foot. Fig. 4 is an enlarged perspective detail of the fixed and grooved plate in which the elevating plate slides. Fig. 5 is an enlarged perspective detail of the indicating plate having the graduations thereon and adapted to be secured to the outer side of the level block.

30 Like numerals of reference indicate corresponding parts in each figure.

35 Referring to the drawings, 1 is the level block having the customary spirit levels 2 and 3, a vertical and grooved recess 4 adjacent to one end and a lateral hole 5 from the bed of one of the grooves of said recess 45 intermediate of its height through to the opposite side of the level.

40 6 is a plate correspondingly formed to the vertical recess 4 having the slide-way 7 centrally recessed at 8 and the flanges 9 through which are the screw holes 10. The plate 6 is securely attached in the recess 4 and has a hole 11 through the recess portion 8 registering with the hole 5.

45 12 is a tube inserted in the hole 5.

50 13 is a flat spring suitably countersunk in the back or the opposite side to the recess 4

of the level block 1 and terminating at the end of the level at the thumb groove 14.

55 15 is a pin rigidly secured to the inner side of the spring 13 and extending inwardly through the tube 12 into the recess 8.

16 is the elevating rack rigidly secured to the plates 17 and extending inwardly therefrom, said rack and said plates being mounted on the foot 18, said foot extending laterally at 19 from said rack and inwardly at 20. The rack 16 and the plate 17 slide upwardly and downwardly in the plate 6, the said rack extending into the recess 8 so that the pin 15 will be in constant engagement with one or another of the teeth. The plates 17 fit into the slide-way 7 and slide upwardly and downwardly therein.

21 is an indicating finger rigid with the rack 16 adjacent to the upper end thereof, 75 said finger extending outwardly from the back of said rack and being bent parallel with the plate 17.

22 is a plate having the graduations 23 thereon and secured in the outer side of the block 1 over one of the plates 17 and under the finger 21 and having the heel portion 24 extending across the back of the rack and secured to said block, said heel portion having the lug 25 extending upwardly forming 85 the recess 26 into which the said finger enters at its lowermost position to reach the lower graduations.

27 is a face plate extending upwardly from the lug 25 and bent over the top of the 90 block 1 and secured on the top and the side of said block.

28 is a face plate extending from the top over the end and top of said block, said plate 28 having a slot 29 uncovering a thumb 95 groove in the bottom of the block 1 up to which said foot 18 reaches in the uppermost position of the rack 16, so that by inserting the thumb in the said groove, uncovered by the slot 29, the foot may be lowered when 100 the rack is released.

30 is a dial secured to the front side of the level block 1 having the points 31 and 32 at right angles as usual in such forms of levels.

105 33 is the pointer pivotally secured in the center of the dial 30 and weighted at the lower end so that it will always hang in a direct downward line and thus obviate the necessity of looking into the spirit levels 110 when that portion of the instrument is out of reach of the eye.

In the use of this instrument, the precise slant of a beam is ascertained by raising the end of the block on the foot 18. This is done by releasing the pin 15 from engagement with the rack 16 in the manner described, and drawing out said foot 18, that end of the block being elevated until the said block reaches the horizontal plane which is determined in the usual way. On 10 the block reaching the horizontal plane, the outward pressure on the spring 13 is released, allowing the pin to again engage the rack. The instrument is then set and the graduations on the graduation plate 23 15 will show the slant per foot. This part of the device will not be described further herein, as many forms of graduating marks may be used. The instrument being set on one slanting beam is ready for use on all 20 of the others, so that precision will be attained in the building up of said beams for roofing or other purposes.

What I claim as my invention is:

1. In a device of the class described, in 25 combination, a block having level indicating devices and a recess toward one end in a side and a hole leading from said recess through to the other side, a plate having a suitable slide-way secured in said recess, a 30 slideable plate arranged in said slide-way plate, a toothed bar rigid with said slideable plate, a foot secured to the lower end of said toothed bar, a pin extending through said hole engaging said toothed bar, and a 35 flat spring secured to the other side of said block and rigidly supporting said pin and

retaining said pin in engagement with said toothed bar.

2. In a device of the class described, in combination, a block having a plurality of 40 level indicating means therein arranged, a vertical grooved recess toward one end thereof and a hole from a groove in said recess through to the opposite side, a plate formed correspondingly to said grooved recess and having a hole through its main recessed portion registering with the aforesaid hole, a rack entering said main recess and slidably arranged therein, plates rigidly secured to said rack and sliding in said 45 grooved plate, an indicating finger rigid with said rack extending rearwardly therefrom and bent over parallel with said plates, a foot rigidly secured to the lower end of said rack and extending laterally therefrom 50 and terminating at the end of said block, a pin extending through said hole and engaging said rack, a flat spring secured at one end to said block on the opposite side from said rack and terminating at the end 55 of said block, a plate having a graduated scale thereon and rigidly secured to said block under said finger and over said plates supporting the rack, and a face plate completing the inclosure of said rack and sliding 60 plates rigidly secured to said block.

Signed at Arthabaska, Province of Quebec, this twenty-third day of June 1910.

ORÉUS L'HEUREUX.
